UNITED STATES PATENT OFFICE.

JOHN DICK, OF EAST PITTSBURGH, THOMAS H. RUTTER, OF HOMESTEAD, AND CHARLES E. LEWIS, OF SWISSVALE, PENNSYLVANIA.

VALVE MECHANISM FOR PUMPS.

1,231,506.

Specification of Letters Patent. Patented June 26, 1917.

Application filed December 2, 1916. Serial No. 134,710.

To all whom it may concern:

Be it known that we, JOHN DICK, THOMAS H. RUTTER, and CHARLES E. LEWIS, citizens of the United States, and residents, respectively, of East Pittsburgh, Homestead, and Swissvale, all in the county of Allegheny and State of Pennsylvania, have invented certain new and useful Improvements in Valve Mechanisms for Pumps, of which the following is a specification.

Our invention relates to the construction of valve mechanisms for pumps, is adapted for use on both the suction and discharge sides of the pumps, and although not limited to such apparatus, is primarily intended for use with high pressure pumps employed in pumping water and other fluids at high or more than average pressures.

Heretofore, so far as we are aware, it has been the practice to inclose the valve mechanism of such pumps within the valve casing so that the operation of the valves is not visible when the pump is in use, and it is necessary to stop the operation of the pump and uncover the valve mechanism in order to adjust the valve mechanism, as becomes necessary from time to time in the operation of such pumps and to determine whether or not the valve and its seat are in working order and the valve is closing tightly on its seat.

One object of our invention is to provide a valve mechanism for pumps having novel means for controlling the opening and closing movements of the valves, and for adjusting the valve mechanism in positioning and regulating the extent of lifting movement of the valve.

Another object of the invention is to provide a valve mechanism having improved means whereby the extent of lifting movement of the valve is made visible and adjustment of the valve and valve operating mechanism is made possible without interruption of the operation of the pump.

A further object of this invention is to provide a valve mechanism for pumps having novel means whereby the extent of lifting movement of the valve in opening is varied without change in the force opposing the lifting movement of the valve, and whereby the force opposing the lifting movement of the valve is lessened or in-

creased at will without variation in the extent of lifting movement.

A further object of the invention is to provide a valve mechanism for pumps having improved means whereby the friction between the sliding parts of the valve mechanism is reduced and leakage at the joints between relatively moving parts of the apparatus is avoided and overcome.

Still further objects of our invention consist in the provision of the novel constructions, combinations, and arrangements of parts shown in the drawing, to be described in detail hereinafter, and to be particularly pointed out in the appended claims.

The drawing forming part of this specification is a sectional elevation showing a pump casing having a valve mechanism constructed and arranged and applied for use thereon in accordance with our invention, the construction shown being adapted for use on either the inlet or suction side, or the outlet or discharge side of the pump.

In the accompanying drawing, the numeral 2 designates the body or casing of a pump valve chamber having openings 3 and 4 connected to one end and adjacent to the opposite end of a transverse opening 5 which forms the valve chamber. One end of the opening forming the chamber 5 extends to the exterior of the casing and is closed by means of a removable flange or cap 6 which is detachably secured in place by bolts 7 and nuts 8. The casing 2 may be located on either the suction side or discharge side of the pump, so that the opening 3 will form either the valve chamber inlet to, or outlet from the valve chamber 5, depending upon the side of the pump on which the chamber 5 is positioned.

The chamber 5 of the casing 2, which is shown located on the suction or inlet side of the pump, is provided at one end with a removable annular seat 9, and positioned on the seat 9 is a lifting valve 10 of the mushroom type. The valve 10 has, on its lower face, a spider 11 which projects downwardly into the opening in the annular seat and forms a guide to maintain the valve in axial alinement with its seat during the opening and closing movements of the valve. The valve 10 also has a beveled face 10^a on its periphery which engages with a simi-

larly beveled face on the seat 9 to form a tight joint therebetween when the valve is in closed position, (or that shown) and projecting from the upper face of the valve 10 is a short integral stem 12.

The stem 12 on the valve 10 has an internally threaded opening therein, into which a cap screw 13 is screwed, the distance this screw projects above the stem 12 being varied in adjusting the seating position of the valve with respect to the casing 2, as becomes necessary when the seat 9 and valve 10, after extended use, are ground or faced.

The head of the cap screw 13 has a conical recess therein which is engaged by the conical end of the valve needle 14, this needle forming a neat sliding fit with and extending through the axial opening in the adjusting stem 15 to form means for connecting the valve 10, which is inclosed within in the valve chamber 5, to the valve spring 16 on the exterior of the valve chamber. A counterbore 17 in the lower end of the stem 15 provides clearance for the head of the cap screw 13, to enable the valve stem 12 to engage with the end of the adjusting stem 15.

The flange or cap 6 has an annular projection 18 on one face, which projects into the valve chamber 5, and the opposite face of this flange has a counterbored axial opening 19 therein, the counterbore 20 of this axial opening being provided with internal screw threads and forming a stuffing box 35 for the adjusting stem 15 which extends through the axial opening 19 and counterbore 20.

The stuffing box formed by the counterbore 20 is provided with a removable seat 21 and with a packing nut or gland 22, which is polygonal in transverse section at its upper end for the attachment of a wrench. The gland 22 is screwed into the stuffing box and engages with the annular ring 23 to compress the packing in forming a tight joint around the adjusting stem 15. The gland 22 also has an internally threaded recess 24 in one end, the threads of which engage with the screw threads 25 on the adjusting stem 15 to hold this stem in adjusted position on the flange 6. A jam nut 26 on the stem 15, which engages with the end of the gland 22, locks this stem in adjusted position.

The outer end of the adjusting stem 15 also is screw threaded and has a shoulder 27 thereon against which the internally threaded end of the hollow spring post 28 is jammed in fastening the post on the adjusting screw, the shoulder 27 being made polygonal in transverse section to afford means for applying a wrench in adjusting the stem 15. The spring post 28 has a set screw 29 in its opposite end for securing the valve spring 16, which is located within the

hollow post, in place, and for adjusting the compression on the spring. The jam nut 30, by engagement with the end of the post 28, locks the set screw 29 in adjusted position.

The openings 31 in the side wall of the hollow spring post 28 enable movement of the needle 14 and spring 16 to be seen when the valve is in operation.

The upper end of the adjusting stem 15 has a counterbore or recess 32 which forms a stuffing box for the needle 14, a packing nut or gland 33 being screwed into the stuffing box on the annular ring 34 to compress the packing in the stuffing box and form a tight joint around the lengthwise movable needle. The needle 14 is made small in diameter so as to lessen the friction between it and the packing in the stuffing box 32, and as the major portion of the length of the needle forms a neat sliding fit within the openings in the gland 33 and adjusting stem 15, the needle cannot bend and bind when transmitting power or force from the spring 16 to the valve 10, or vice versa.

A spring centering cap or follower 35 is positioned between the outer end of the needle 14 and one end of the spring 16, and a similar follower 36 connects the other end of the spring with the conical end of the set screw 29 in the outer end of the spring post 28, the valve spring 16 being held in position within the hollow spring post 28 by engagement with the projections 37 and 38 on the faces of the followers 35 and 36.

By reference to the drawing it will be readily seen that the operation of the valve 10 within the valve chamber 5 is indicated or made visible by the movement of the outer end of the needle 14, and the spring 16, which are on the exterior of the valve chamber 5.

It will also be seen that the valve 10 may be positioned within the valve chamber 5 in various locations to suit the seat when the valve and seat are re-ground or re-faced, without changing the amount of compression on the valve spring 16, by suitably adjusting the cap screw 13 in the end of the stem 12 of the valve. The extent of lifting movement of the valve 10 is regulated by means of the adjusting stem 15, as the end of the valve stem 12 engages with the adjacent end of the adjusting stem 15 so that by varying the position of the adjusting stem 15 in the casing 2 relative to the valve 10 the lifting movement of the valve may be changed. When the lifting movement of the valve 10 is changed the compression of the spring 16 will be regulated by means of the set screw 29 in the upper end of the hollow spring post 28.

The advantages of our invention will be apparent to those skilled in the art.

Modifications in the construction and ar

angement of the parts may be made without departing from our invention as defined in the appended claims.

I claim:—

5. 1. A valve mechanism comprising a valve casing having a valve chamber, a lifting valve in the chamber, said chamber having inlet and outlet openings extending thereto, said openings being on opposite sides 65 of said valve, a cap closing one end of the valve chamber and having an axial opening therein, an adjusting stem mounted in the axial opening and having an axial opening therein, a hollow spring post on the outer end of said stem, a coil spring within the hollow post, and a sliding needle extending through the axial opening in said stem and operatively connecting said spring and lifting valve. 70
10. 2. A valve mechanism comprising a valve casing having a valve chamber, a lifting valve in the chamber, said chamber having inlet and outlet openings extending thereto, said openings being on opposite sides 75 of said valve, a cap closing one end of the valve chamber and having an axial opening therein, an adjusting stem mounted in the axial opening and having an axial opening therein, a hollow spring post on the outer end of said stem, a coil spring within the hollow post, and a sliding needle extending through the axial opening in said stem to connect the spring and valve, and adjusting means on the spring post to engage the 80 spring in regulating the compression on said spring. 85
15. 3. A valve mechanism comprising a valve casing having a valve chamber, a lifting valve in said chamber, said chamber having inlet and outlet openings extending thereto, said openings being on opposite sides 90 of the valve, a cap closing one end of the valve chamber and having an axial opening therein, an adjusting stem mounted in the axial opening and having an axial opening therein, means for adjusting the 95 stem on said cap, a hollow spring post on the outer end of said stem, a coil spring within the post, and a sliding needle extending through the axial opening in said stem and operatively connecting said spring and lifting valve. 100
20. 4. A valve mechanism comprising a valve casing having a valve chamber, a lifting valve in said chamber, said chamber having inlet and outlet openings extending thereto, said openings being on opposite sides 105 of said valve, a cap closing one end of the valve chamber and having an axial opening therein, an adjusting stem mounted on the cap, said stem having an axial opening therein, a spring post on the outer end of said stem, a spring on the post, and a sliding needle extending through the axial opening in said stem to connect the spring and lifting valve with said spring. 110
25. 5. A valve mechanism comprising a valve casing having a valve chamber, a lifting valve in the chamber, said chamber having inlet and outlet openings extending thereto, said openings being on opposite sides 115 of said valve, a cap closing one end of the valve chamber and having an axial opening therein, an adjusting stem mounted in the axial opening and having an axial opening therein, means for packing the joint between said cap and adjusting stem, a spring post on the outer end of said stem, a spring on the post, a sliding needle extending through the axial opening in said stem and connecting said valve with the spring, and means for packing the joint between said stem and needle. 120
30. 6. A valve mechanism comprising a valve casing having a valve chamber, a lifting valve in said chamber, said chamber having inlet and outlet openings extending thereto, said openings being on opposite sides 125 of the valve, a cap closing one end of the valve chamber and having an axial opening therein, an adjusting stem mounted in the axial opening and having an axial opening therein, means for packing the joint between said cap and adjusting stem, a spring post on the outer end of said stem, a spring on the post, a sliding needle extending through the axial opening in said stem and connecting said valve with the spring, and means for packing the joint between said stem and needle. 130
35. 7. A valve mechanism comprising a valve casing having a valve chamber, a lifting valve in the chamber, said chamber having inlet and outlet openings extending thereto, said openings being on opposite sides 135 of said valve, a cap closing one end of the valve chamber, an adjusting stem adjustably mounted on the cap, said stem having an axial opening therein, a spring post on the outer end of said stem, a spring on the post, and a slideable needle extending through the opening in said stem to connect said lifting valve with said spring. 140

In testimony whereof we have hereunto set our hands.

JOHN DICK.

THOMAS H. RUTTER.

CHARLES E. LEWIS.
